CUTTING, STRETCHING, AND TWISTING

Ralph C. Martin, Cuyahoga Falls, Ohio, assignor
to Wingfoot Corporation, Wilmington, Del., a
corporation of Delaware

Application August 2, 1940, Serial No. 349,881

2 Claims. (Cl. 57—34)

This invention relates to apparatus designed for cutting, twisting and stretching thin sheet material, such as rubber hydrochloride film. The invention includes both the apparatus and the method employed using the apparatus.

It has previously been suggested that a narrow ribbon of rubber hydrochloride film, for example, a strip several inches wide, be continuously rolled on the bias with heat and pressure, and while stretching the film, to produce a thin thread or filament of compacted stretched rubber hydrochloride. The stretching aligns the rubber hydrochloride molecules and increases the strength of the filament. By using heat and pressure the overlapping surfaces of the film are united, and a compact filament results. For certain purposes such a compact thread or filament is very useful.

This invention relates to the loose twisting and stretching of a rather narrow strip or strand of rubber hydrochloride film. Such a loosely twisted product has different properties from the compact article of the prior art just described and is particularly designed for use in weaving rugs, tapestries, upholstery, etc. The crinkling of the thin stretched film which results from twisting causes a reflection of light from the film which is attractive in that it gives the appearance of great life to the article. The stretching gives desired strength. The material is inherently waterproof. By weaving films which are differently colored by dyes or pigments or metallic powders, pleasing decorative effects are produced.

The apparatus of this invention is designed for the production of the loosely twisted strand on a commercial scale. It provides for cutting the strips to be twisted from a roll of the film and stretching and twisting these strips. The apparatus may be easily made by suitable adaptation of one of the conventional cotton twisters now available on the market, such as a Saco-Lowell type of twister. The invention will be further described in connection with the accompanying drawing in which Fig. 1 is a view in perspective of the apparatus of the invention, and Fig. 2 is a front view of the same.

The roll of cast rubber hydrochloride film 1 from which the twisted strips are to be formed is supported on any suitable bar 2. The film 3 is brought from this roll 1 over the roll 4 which is mounted on the arms 5 which are held by the spring 6 so that the roll 4 is continuously held against the roll of film 1, regardless of whether the roll 1 is large as at the first of a

run, or small as near the end of a run when the film on the roll 1 has been almost entirely used. As the film leaves the roll 4, it is split by the knife blades 7 which are supported by the bars 8, which are supported from the bar 5 by hinges and held in position by a spring. The purpose in mounting the knives and the roll 4 on movable bars is to give flexibility to the machine to facilitate threading film through the machine to start operations.

The drawing shows three knife blades 7 which split the film into four parts 9. This is illustrative only. Any number of knives may be used. Ordinarily the film will be cut into strips about one inch wide. The strips may be as wide as two inches or wider, and as narrow as one-half inch or narrower. The strips are passed under the roller 10 and then through the ring 11 which prevents their separating prematurely and ripping the film ahead of the knife blades 7. From the ring 11, the separate strips 9 are fed around grooved guides 12 to suitable heating means. Other heating means may be substituted for that here shown which comprises the rolls 13, 14 and 15. The rolls 13 and 14 in the design shown are long rolls extending preferably the width of the machine. One or both of these rolls are driven rolls. The short rolls 15 rest on the rolls 13 and 14 and are driven by them. Guide means (not shown) keep the rolls 15 from migrating to the left or right. From the roll 14 the individual strips of film pass over the bar 16 through the eyes 17 to the twisting mechanism.

The twisting mechanism may be of any usual design. As shown, it comprises the spindles 18 driven by belts (not shown) which pass around the pulleys 19. Over the spindles are the spools 20 which are rotated at a high speed by the spindles. The bar 21 is mounted so that it moves vertically up and down over the length of the spools as the twisted film is wound onto the spools. The spools are located within holes in the bar 21. The bar 21 is equipped with the usual rings 22 on which the travellers 23 of the usual type circulate in winding the twisted strips on the spools. The equipment indicated by the numerals 17 through 23 inclusive may be of a conventional type and operated in the conventional manner.

In passing from the roll 1 to the spool, the film is heated and stretched. The most satisfactory place for applying heat is through the roll 14. This roll may, for example, be heated to such a temperature that in passing over the roll the

film is heated to a temperature around 90 to 100° C. The pressure of the roll 15 on the roll 14 maintains the rate of feed of the film over the roll 14. The winding mechanism is so geared that the twisted strip is wound on the spool at a greater lineal speed than that at which it passes over the roll 14. It is wound on the spool at a speed at least double that of the surface speed of the roll 14 and may be wound at a rate four or five or more times that of the surface speed of the roll 14. This stretches the heated film and the stretch normally takes place just as the film leaves the roll 14. The film is kept in a flat condition from the supply roll 1 until it passes over the bar 16. After it leaves the bar 16, it is twisted by the movement of the traveller in the way that cotton yarn is commonly twisted. The film is quickly cooled by the air and its temperature is lowered to the point where on twisting, the overlapping, contacting plies do not become heat-sealed together. The twist imparted to the film may be about one and one-half to two and one-half turns per inch to a narrow ribbon of the film which is about one inch wide and only a fraction of a hundredth of an inch thick. Ordinarily the film supplied to the apparatus will be about .001 of an inch thick. It may be transparent or colored with a pigment or dye. It may contain a stabilizer, such as hexamethylene-tetramine.

The bar 16 may be replaced by a driven roller, and by driving it at a greater surface speed than the roller 14, so that by properly heating the film it is stretched in passing between these rollers.

As described in the co-pending application of

Gerald D. Mallory, Serial Number 349,644, filed Aug. 2, 1940, the device may be used for producing a film which will not untwist by providing means for supplying adhesive or solvent to the film before or during the twisting operation. The solvent or cement, for example, may be supplied to the film as it passes over the bar 16. This may be accomplished by any usual means, such as an applying roll which dips into a bath of liquid adhesive or solvent. Drying means should be provided to insure removal of all liquids from the final product before twisting. As described in the Mallory application, two or more of the strips of film may be brought together and twisted simultaneously. The drawing is illustrative and modifications may be made.

I claim:

1. Apparatus for stretching, twisting and winding film which comprises a feed roller, a plurality of knives for slitting the film into strips, a heated roller with separate means for passing each strip over the roller and means for twisting each separate strip of film and simultaneously winding it at a speed higher than the speed of travel of the surface of the heated roller.

2. The method of treating cast rubber hydrochloride film continuously which comprises slitting a sheet of the same into a plurality of strips, heating each strip and stretching it while preventing it from twisting and then cooling, twisting and winding each strip separately and separately winding it at a higher rate than that at which it is heated so that each strip of the heated film is stretched.
